UNITED STATES PATENT OFFICE.

MARTIN A. KLEIN, OF NEW YORK, N. Y.

DESIGN FOR A NECKLACE.

Application filed August 18, 1924. Serial No. 10,477. Term of patent 14 years.

To all whom it may concern:

Be it known that I, MARTIN A. KLEIN, a citizen of the United States, and a resident of the city of New York, borough of the Bronx, in the county of Bronx and State of New York, have invented a new, original, and ornamental Design for Necklaces, of which the following is a specification, reference being had to the accompanying drawing, forming part thereof.

The figure is a plan view of a necklace showing my new design.

I claim:

The ornamental design for a necklace, as shown.

MARTIN A. KLEIN.
